DIFFERENTIATING MECHANISM.

1,180,924.

Specification of Letters Patent. Patented Apr. 25, 1916.

Application filed April 7, 1915. Serial No. 19,678.

To all whom it may concern:

Be it known that I, MARTIN HVEEM, a citizen of the United States, residing at Bayles, in the county of Shasta and State of California, have invented new and useful Improvements in Differentiating Mechanism, of which the following is a specification.

This invention relates to a differentiating mechanism.

The object of the present invention is to provide a simple, substantial, cheaply manufactured differential particularly applicable to driving shafts in motor cars and the like, which is so constructed that compensating movement is obtained without the use of gears and the like now usually employed, thereby simplifying construction and permitting the engine power to be equally transmitted to the driven axles and wheels and at the same time leaving either axle or wheel free to take the initiative during the periods of increased or decreased speed.

The invention consists of the parts and the construction and combination of parts as hereinafter more fully described and claimed, having reference to the accompanying drawing, in which—

Figure 1 is a longitudinal section through the differential, showing it connected with the rear driving wheels of a car. Fig. 2 is an enlarged longitudinal section of the differential. Fig. 3 is a section on line 3—3 of Fig. 2. Fig. 4 is a perspective view of shaft 6 and one-half of casing 2. Fig. 5 is a perspective view of one of the casing sections.

Fig. 1 indicates a casing which in this instance forms a closure for the differential mechanism generally indicated at B. Mounted interiorly of casing A is a second casing 2, and extending longitudinally through said casing are the rear driving axles of the car indicated at 3 and 4. These axles are centrally divided and their inner ends are slightly enlarged, as indicated at 5, to form heads which are journaled interiorly of the casing 2. Extending through casing 2, at right angles to the axles 3 and 4, between the abutting ends or heads 5, is a shaft 6. This shaft is journaled in the casing and is also adapted to slide in same.

Formed on each side of shaft 6 is a spherical or ball-like projection 7, and formed in the abutting or adjacent face of the heads 5 is a recess 8 into which the sphere-like

projections extend. The recesses 8 are eccentrically disposed with relation to the center of the axles 3 and 4, thus forming a crank-like connection between shaft 6 and the axles 3 and 4.

The casing 2 is centrally divided, as indicated at 9, to permit the insertion of the shaft 6 and a general assembling of the differential mechanism, and the driving gear, such as indicated at 10, is secured to either one or the other of the sections forming the casing. Driving movement is transmitted directly to gear 10 and the connected casing 2 by means of the pinion 11 in the usual manner; the driving shaft being connected with the engine.

From the foregoing description it will be seen that the differential mechanism as a whole consists of a casing 2 to which revolving movement is transmitted through gears 10 and 11, and that revolving movement of same is transmitted to the axles 3 and 4 by means of shaft 6 and the spherical projections formed thereon; the coupling formed between shaft 6 and axles 3 and 4 being in reality nothing more or less than a universal joint.

In operation, when driving straight ahead, that is when the rear wheels, with connected axles 3 and 4, revolve at the same speed, it will be seen that power is transmitted directly from the revolving casing 2 to the axles 3 and 4 by means of shaft 6 and projections 7, said projections forming, in this instance, a crank-like connection between the two axles. If the vehicle passes around a turn, for instance in the direction of arrow a, it will readily be seen that the outside wheel 12, with connected axle 3, will have to turn a greater number of revolutions than the inner wheel 13 with connected axle 4. This is permitted in the present instance as shaft 6 will reciprocate with relation to casing 2 sufficiently to permit projection 7 to turn in a circle about the center of axle 3 with projection 7 as a center. In fact, it would be possible for axle 4 to remain entirely stationary while axle 3 is turning. Projection 7 will in that instance act as a pivot about which projection 7 turns, the reciprocating mounting of shaft 6 permitting this movement.

A simple, substantial differential mechanism is in this instance obtained without the use of gears of any kind. The power from

the engine may be quickly transmitted to the axles 3 and 4, with connected wheels, and the axles are at the same time free to take the initiative during periods of increased speed.

The materials and finish of the several parts of the mechanism are such as the experience and judgment of the manufacturer may dictate.

10 I wish it understood that various changes in form, proportions and minor details of construction may be resorted to within the scope of the appended claims and that I do not wish to limit myself to the specific design and construction here shown.

Having thus described my invention, what I claim and desire to secure by Letters Patent is—

1. A differential mechanism comprising a main casing having axle bearings and another bearing within the casing, a second casing comprising component sections formed with aligned axle bearings, each casing section having a cylindrical portion formed with a concentric cavity, the abutting edges of the casing sections being formed with a transversely disposed shaft bearing, a gear fixed on the cylindrical portion of one casing section, the cylindrical portion of the component section being journaled in said other bearing of and receiving support from the main casing, a pair of axles arranged in the axle bearings of the main and second casings, each shaft having a head enlargement snugly fitting in the cavity of

the respective section and formed with a recess, and a shaft slideable in the shaft bearing of the second casing and provided with lateral projections engaging in the recesses of the axle head enlargements.

2. A differential mechanism comprising a casing centrally divided to form sections each of which is provided with a central cavity having a concentric axle bearing and a transversely and diametrically arranged shaft bearing provided on the abutting edges of the casing sections, a pair of aligned axles disposed in the axle bearings of the casing and each provided with an enlarged head conforming with and snugly fitting in the cavity of the respective casing section, the opposing faces of the axle head enlargements being provided with recesses, a unitary shaft slideable in and through the shaft bearing of the casing to project therebeyond and provided with integral, lateral, ball projections movably engaging in the recesses of the axle head enlargements which abut the shaft and a gear fixed on a casing section about the cavity therein whereby the snugly fitting axle head will render support for the gear on excessive strain on the latter.

In testimony whereof I have hereunto set my hand in the presence of two subscribing witnesses.

MARTIN HVEEM.
